UNITED STATES PATENT OFFICE

2,446,993

DEVICE FOR FACILITATING
CIRCUIT DESIGN

Joseph Alter, Long Branch, N. J.

Application December 19, 1944, Serial No. 568,920

1 Claim. (Cl. 179—171)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to electronic circuit measuring devices and more particularly to a device for determining the optimum value of circuit elements at audio or radio frequencies.

The invention herein considered is similar in construction to the familiar commercial tube testers, but differs in the method of operation and final results.

The invention was conceived with the object of overcoming the tedious and time wasting so-called "bread board" method of determining circuit parameters.

The "bread board" procedure is well known to those versed in the art of electronic circuit design, but for the sake of pointing out the economy made possible by use of this invention, a brief outline of "bread board" procedure is presented.

For example, a wooden board is used as a base for arranging the various components of a single stage voltage amplifier. The said components, such as resistors, condensers, sockets, electron discharge valves, etc., are roughly wired together. Proper voltages are applied to this arrangement and the result noted. During this process, resistance, capacitance and other values are changed about until an optimum result is attained. The established values of the various components are then measured and noted in the usual manner.

The aforementioned procedure consumes time, and when completed the experimental stage thus set up is taken apart, and this process consumes additional time.

The use of the invention would obviate the necessity for setting up an experimental stage or stages and the subsequent dismantling of same. The means for accomplishing the same experimental procedure in a rapid, efficient and time-saving manner will be described in detail hereinafter.

The invention contains valve sockets to accommodate any of the commercial type electronic discharge valves together with circuit means for applying the required type and values of voltage to the elements of an electronic discharge valve.

The aforementioned combination of socket and circuit means are designed to represent a single stage of voltage or power amplification applicable to either radio or audio frequencies.

2

The invention will now be described by referring to the accompanying drawing, in which:

Fig. 1 is a schematic diagram of an embodiment of this invention, and

Fig. 2 depicts the panel layout of such an embodiment.

Referring to Fig. 1, an electron discharge valve 1, in this example a pentode (although sockets to accommodate the various commercial type valves are provided in this embodiment), has in series with the various elements thereof, 2, 3, 4, 5 and 6, a plurality of variable resistors, 7, 8, 9, 10 and 11 for regulating the amount of voltage impressed on the aforementioned elements of the electron discharge valve.

A variable capacitor 12 functions as a coupling condenser to an output load 17 whilst the capacitors 13 and 14 act as by-pass condensers for cathode and "B" voltage supply, respectively. A plurality of switches 16 serve to indicate the variable resistor in use by switching on the appropriate indicating lamps 15. The said switches 16 are operated by rotation of the variable resistors 7, 8, 9, 10 and 11 in a manner familiar to those acquainted with the art.

In fact, the aforementioned switches may be standard variable resistance controls provided they are capable of carrying the current in the particular circuit where they are used. Switch 16A is provided to permit the insertion of capacitor 13 into the circuit as desired.

To indicate optimum operating conditions a galvanometer 38 or other suitable indicating instrument may be shunted across the output load 17, as illustrated.

Referring now to Fig. 2, the panel layout contains thereon a plurality of sockets 21, 22, 23, 24, 25, 26, 27 and 28 to accommodate any of the well known commercial type electron discharge valves.

40 Affixed to the said panel in conjunction with the variable resistors and capacitors are calibrated dials 29, 30, 31, 32, 33, 34, 35 and 36 indicating the values of said resistors and capacitors for predetermined values.

45 Indicating lights 16 are placed above each calibrated dial and serve to inform the operator which resistance or capacitance is being used and in what part of the circuit.

Input terminals 19 are provided to accommodate 50 the signal voltage source 37. However, if desired, the source of signal voltage 37 may be incorporated in the invention. Output terminals 18 are used to insert an artificial load 17 or a load such as an output transformer, etc.

55 Certain general values of resistance and ca-

pacitance have been established in electronic design work and such information is available in texts covering the subject, but in order to establish optimum operating conditions such resistive and capacitive values must be varied until the desired operating condition results.

Let us assume that a single stage of audio amplification is being designed and that a pentode type electronic discharge valve is to be used.

The pentode valve is placed in socket 23 and power supply 20 is put into operation. The approximate value of plate resistance is inserted in the circuit by manipulation of the variable resistor 11 as indicated on the calibrated dial.

The same procedure as above is followed for the screen resistance, by manipulating variable resistor 10, etc. Proper bias resistance is accomplished by use of variable resistor 9.

To properly match the input impedance of valve 1 it is only necessary to know the impedance of the input signal source and then adjust variable resistor 7 accordingly. The voltage on the grid element 3 may be further controlled by variable resistor 8.

All of the previous adjustments are set with respect to general values. As is well known, these values are obtainable from engineering texts, handbooks, etc. on the subject of electronic circuit design. The use of the indicating meter 38 permits the further manipulation of the various variable resistance and capacitance controls until optimum operation is arrived at as shown on the meter 38.

Thus optimum operation for each stage in an electronic circuit can be rapidly consummated in a minimum of time. The invention is adaptable for the determination of optimum circuit parameters in practically any electronic circuit using electronic discharge valves of the evacuated or gas-filled types.

While what has been described is the preferred embodiment of the invention, it will be apparent to those versed in the art that various changes in arrangement and cooperation of parts 5 may be resorted to without departing from the spirit of the invention or the scope of the claim.

Having thus described the invention, what is claimed is:

A device for determining circuit parameters, under predetermined signal conditions, of electronic circuits comprising an electron tube, a plurality of terminals adapted to be connected to the electrodes of said tube, means for supplying operating potentials to said electrodes, a plurality of components in circuit with said means and said electrodes, each of said components having calibrated adjusting means to vary the magnitude thereof, signal generator means for impressing a signal upon the input electrodes of said tube, load means in the output circuit of said tube for extracting a signal output, and means in said output circuit for indicating signal output conditions as said components are varied in magnitude whereby the magnitude of each component is determinable at any signal output condition.
